UNITED STATES PATENT OFFICE.

BERNARD J. McCABE, OF DETROIT, MICHIGAN.

UMBRELLA.

1,109,854.

Specification of Letters Patent.

Patented Sept. 8, 1914.

Application filed January 2, 1913. Serial No. 739,693.

To all whom it may concern:

Be it known that I, BERNARD J. McCABE, citizen of the United States, residing at Detroit, in the county of Wayne and State of Michigan, have invented certain new and useful Improvements in Umbrellas, of which the following is a specification.

This invention relates to improvements in umbrellas, more particularly to umbrellas having means for automatically opening and closing, and has for one of its objects to increase the efficiency and utility of devices of this character.

Another object of the invention is to provide a device of this character wherein the ribs are formed integral throughout and with portions of the ribs resilient.

Another object of the invention is to provide an implement wherein the ribs and spreaders are integral and portions of the ribs resilient.

With these and other objects in view the invention consists in certain novel features of construction as hereinafter shown and described and then specifically pointed out in the claims, and in the drawings illustrative of the preferred embodiment of the invention, Figure 1 is an elevation of the improved umbrella partly in section without the fabric covering and the parts in collapsed or folded position. Fig. 2 is a sectional elevation of the parts shown in Fig. 1. Fig. 3 is a view similar to Fig. 2 with the tip section distended. Fig. 4 is a sectional view of the "stick" or main tube portion. Fig. 5 is an enlarged view of one of the combined ribs and spreaders. Fig. 6 is a view similar to Fig. 2 with the ribs and spreaders distended or in open position. Fig. 7 is an enlarged transverse section on the line 7—7 of Fig. 6. Fig. 8 is an enlarged vertical section of the resilient rib holder. Fig. 9 is an enlarged transverse section on the line 9—9 of Fig. 8. Fig. 10 is an enlarged sectional detail of the runner member showing the spring connection. Fig. 11 is a section on the line 11—11 of Fig. 10.

Corresponding and like parts are referred to in the following description and indicated in all the views of the drawings by the same reference characters.

The improved umbrella includes a tubular "stick" or rod 10 having a handle 11 at one end with the tubular stick extending

for a distance into the handle, as shown. 55 The stick 10 is provided near the handle portion with a transverse slot 12 and with slots 13—14—15—16 and 47 intermediate its ends, the object to be hereafter explained. Slidably disposed within the outer portion of the stick is a tip or plunger section comprising an outer tubular portion 17 reduced for the major portion of its length, as shown at 18, and terminating in an outwardly directed catch or lug 19. The reduced portion 18 of the tip section is enlarged intermediate its ends, as shown at 20, and provided with a transverse holding bar 21 in the enlarged portion, the ends of the bar extending through the slots 16 in 60 the stick member 10. A finial or tip 22 is inserted in the outer end of the tubular portion 17 of the tip section of the ordinary form. Slidable over the stick a distance from its outer end is a runner sleeve 65 23 having a plurality of annularly arranged sockets 24 to receive the inner ends of the spreaders, which are movably coupled to the runner. A pin 25 extends through the stick and the sleeve 23 and operates in the longitudinal slots 47 in the stick and is secured in place by a cotter pin 25'. The reduced portion 18 of the tip section operates at one side of the pin 25 as shown, and the tip section is therefore not interfered with in 70 its operation by the presence of the pin. Slidable over the stick 10 is another sleeve 75 26, while a coil spring 27 encircles the stick and is extended at one end through the portion 24 of the runner 23 and engages the pin 25, as shown more clearly in Figs. 10 and 11. Slidable over the stick 10 is another and longer sleeve 28 having a lateral lip 48 at its upper end and slot 28' in one side and with a transverse pin 29 which extends 80 through the slot 13 of the stick. Located within the stick is a rod 30 having an eye at one end engaging around the pin 25. At its free end the rod 30 is provided with a lateral enlargement or catch 31 adapted 85 to engage through the slot 15 and against the outer end of the longer sleeve 28. The rod 30 lies against the pin 21 as shown, the object to be hereafter explained. Another rod 32 is located within the stick and is 90 enlarged into an eye at one end to engage around the pin 29 and extends at its other end to the handle 11. A block 33 is con-

nected to the rod 32 and provided with a thumb button or trip rod 34 which extends through the slot 12 of the stick. Extending through the portion of the stick which is located within the handle 11 is a pin 35, and a coil spring 36 is connected at one end to the pin 35 and at the other end to the lower terminal of the rod 32. By this means the spring 36 exerts its force to hold the rod 32 yieldably and normally in its lower position, as hereafter explained.

The ribs of the improved umbrella each comprises a lower relatively stiff portion 37 and a thinner resilient upper portion 38, the two parts 37-38 being integral and enlarged, as shown at 39, where the thinner portion leaves the larger portion. Extending from the enlarged portion 39 of each rib is a spreader member 40 which is integral with the enlargement, the spreader being perforated at its free end to receive the holding member by which the spreaders are secured in the sockets 24. At their free outer ends the resilient portions 38 of the ribs are bent laterally to a limited extent as shown at 38'', and the terminals tapered as shown at 38''' and with a lateral offset intermediate the bent portion, the object to be hereafter explained.

30 The upper end of the stick 10 is externally threaded and is provided with a plurality of transverse apertures shown at 41 corresponding in number to the ribs and their respective portions, and designed to receive the lateral projection 38' of the respective portions 38 of the ribs, as shown. By this means when the ferrule 42 is screwed "home" the ribs are firmly coupled to the stick. The apertures 41 are arranged in "staggered" relations, so that they do not unduly weaken the stick, and the projections 38' are located in position to enter the apertures.

When the tip section 17 is forced backward into the stick the pin 25 is held stationary by the holding bar 30 whose latch 31 engages in the slot 15, but the stick during the inward movement carries the pin or closing bar 21 with it, and the bar 21 by passing through the oblong slots in the stick and likewise passing through the sleeve 26 and through an eye on the end of the spring 27, puts a strain upon the spring 27. When the tip section has been pressed far enough backward the latch 19 will engage in the slot 14, which action holds the plunger section in a locked position within the stick, with the latch 31 engaged within the slot 15 and holding the spring 27 under tension and ready to force the ribs into open position when released, as hereafter explained. The runner member is not affected by this action, but this movement of the tip section is necessary to enable the bar 30 to be engaged by its latch 31 in the slot 15 and thereby supported against

the strain of the spring 27 which is exerted on the pin 25 to hold the runner in position with the spring 27 under tension.

To open the umbrella the button 34 is pushed upwardly carrying the block 33 with it and likewise forcing the rod 32 longitudinally of the stick against the resistance of the spring 36, and the pin 29 carrying the sleeve 28 and the lip 48 at the upper end of the sleeve 28 forces the latch 31 back out of the slot 15 of the stick, which movement allows the spring 27, which is under tension, to draw the runner 23 downwardly or toward the handle and the runner 23 forces the ribs into elevated position as shown in Fig. 6, thereby causing the upper parts of the ribs 38 to curve outwardly as they are held permanently rigid at the tip by the ferrule 42 and to the back of the rib 37 by the encircling enlargement 39. The curved portions of the ribs 38 are the closing springs of the ribs, each rib having its own independent closing portion 38. This inward movement of the tip section expands or stretches the spring 27 through the action of the pin 21 which engages the sleeve or runner member 26 with it over the stick.

When the umbrella is to be closed, the operator forces the thumb pin or knob 34 outwardly or toward the handle, and thus causes the rod 32 to move the sleeve 28 a corresponding distance downwardly and also forces the sleeve to release the latch 19 and likewise release the tip section, and then the resilient parts 38 of the ribs return to their original position parallel to the stick, as said resilient portions 38 are under tension when in curved position, as shown in Fig. 6. When the tip section is released the resilient portions of the ribs 38 simply straighten out and constitute the closing mechanism of the umbrella.

Slidable over the stick 10 near the slot 12 is a slide 43 having an annular curved flange to receive the globular "tips" 45 of the portions 37 of the ribs, and thus hold the ribs together with their fabric covering in closed position. Each of the portions 37 of the ribs is provided with an eye 46 near its free end to receive the threads whereby the cover is attached to the ribs.

When in folded or collapsed position, the tip section is preferably released and disposed in its outer position with the opening and closing spring 27 relaxed to avoid danger of the umbrella being accidentally or prematurely opened.

The release of the springs 27 causes the ferrule member 23 to be moved downwardly or toward the handle and likewise releases the resilient portions 38 of the ribs and causes them to automatically curve outwardly and assume the position shown in Fig. 6 with the spreader portions 40 of the ribs disposed substantially at right angles.

to the stick. The runner member 23 is not affected by this movement of the plunger section for the reason that the ribs 36-38 are disposed substantially in longitudinal alinement with the spreaders 40.

Having thus described the invention what I claim is:

1. An umbrella including a stick, a plurality of ribs each having a resilient portion, means for rigidly connecting each of said resilient rib portions at one end to the stick, a runner slidably on said stick, means for movably coupling said ribs to said runner, a spring connected to said runner, a plunger section movable relative to said stick and connected to the spring and operating to place the spring under stretched tension when actuated, means for locking said plunger section in its inner position, and means for releasing said plunger section.

2. An umbrella including a stick, a plurality of ribs each having a resilient portion secured at one end to the stick, a runner upon the stick, spreaders connected respectively to said runner and to said ribs, a spring connected to said runner, means for placing said spring under tension, means for holding said runner against the pull of said spring, and means for releasing said runner.

3. An umbrella including a tubular stick, a plurality of ribs each having a resilient portion secured at one end to the stick, a runner upon the stick, spreaders connected respectively to said runner and to said ribs, a plunger operating in said tubular stick, a spring connected at one end to said runner and at the other end to said plunger and thereby placed under tension when the plunger is moved into its inner position, means for releasing said runner to permit the automatic opening of the umbrella, and means for releasing said plunger to enable the umbrella to be closed by the action of the resilient portions of the ribs.

4. An umbrella including a tubular stick, a plurality of ribs each having a resilient portion connected at one end to said stick, an outer runner member slidable on said stick, means for movably coupling said ribs to said outer runner member, an inner runner member, a spring connecting said runner members, a plunger section slidable in said stick, means for coupling said plunger section to said inner runner member to cause the plunger section to apply strain to the spring when moved into the stick, means for locking said plunger section to the stick when in inner position, and means for releasing said lock.

5. An umbrella including a tubular stick, a plurality of ribs each having a resilient portion connected at one end to said stick, an outer runner member slidable on said stick, means for movably coupling said ribs to said outer runner member, an inner run-

ner member, a spring connecting said runner members, a plunger section slidable in said stick and having a reduced intermediate portion and a resiliently supported latch at the inner end adapted to engage with the stick and locking the plunger section thereto when the tip section is moved into the stick against the resistance of the spring, a pin extending transversely of the plunger section, a resilient rod connected at one end to the outer runner member and with a lateral latch at the other end, said rod being arranged to pass over said plunger section pin and deflected laterally thereby, and means for consecutively releasing the plunger section latch and the resilient rod latch and the spring held under tension thereby.

6. An umbrella including a tubular stick, a plurality of ribs each having an outer resilient portion connected at one end to said stick, an outer runner member slidable on said stick, an inner runner member slidable on said stick, means for coupling said ribs to said outer runner member, an opening spring coupled to said runner members, a plunger section connected to said spring and operating to apply tension to the same, and means for releasing said spring.

7. An umbrella including a stick, ribs each having a resilient portion and connected thereby to the stick, a runner on the stick, spreaders connected between the runner and the ribs, a plunger movable relative to the stick, a spring connected to the runner and to the plunger and placed under tension by the plunger when moved into its inner position, a sleeve slidable upon the stick, a locking device carried by the runner and extending into the path of the sleeve, a catch device carried by the plunger and extending into the path of the sleeve, and means for moving said sleeve, whereby the locking device is released and the umbrella permitted to open when the sleeve is moved in one direction and the plunger released to permit the umbrella to close when the sleeve is moved in the opposite direction.

8. An umbrella including a tubular stick, a runner slidable upon said stick, ribs each including a resilient portion connected at one end to said stick, connecting means between the ribs and the runner, an opening spring connected to said runner, a plunger section slidable in said stick and connected to said spring and operating to apply tension thereto when in inner position, a latch carried by said plunger section, a sleeve slidable on said stick and through which said plunger section latch operates, a rod coupled to said sleeve, an equalizing spring connected to said rod, and means for moving said rod longitudinally of said stick, whereby the opening spring is released and the ribs opened when the rod is moved in one direction against the resistance of the

- equalizing spring, and the ribs moved into closed position when the rod is moved in the opposite direction against the resistance of the equalizing spring.
5. An umbrella including a stick having a plurality of transverse apertures at its outer end, a runner slideable on said stick, a plurality of ribs each having a resilient portion provided with a lateral projection spaced from its outer end and with the portions of the ribs tapered in advance of the projection engaging respectively in the apertures of the stick, a ferrule engaging over the resilient portions of the ribs including the lateral projections and internally tapered to engage the tapered portions of the ribs, and means for movably coupling said ribs to said runner.

10. An umbrella including a stick, a runner, ribs having resilient rib closing portions and connected to the stick, spreaders between the runner and the ribs, a spring connected to the runner, means for holding said spring under tension, means for holding said ribs in closed position against the pull of said tension spring, means for releasing said rib holding means to enable the umbrella to open, and means for releasing said spring to permit the umbrella to close.

In testimony whereof I affix my signature in presence of witnesses.
